RIDING SADDLE

Joseph A. Greene, Louisville, Ky.

Application June 19, 1933, Serial No. 676,415

9 Claims. (Cl. 54—44)

This invention relates to riding saddles of the types commonly used on horses and like animals. These saddles heretofore have been provided with stirrups permanently secured to opposite sides of the saddle, and with a girth extending around the belly of the horse from one side of the saddle to the other side thereof. In securing the saddle, it is desirable to tighten the girth sufficiently to prevent the saddle either from turning when any weight is placed on either stirrup or from slipping rearwardly or forwardly along the body of the horse. A girth tight enough to prevent turning has the disadvantage not only of causing considerable discomfort to the horse, but of permitting backward or forward movement of the saddle relatively to the horse unless tightened to the extreme. Furthermore, because of this discomfort, a horse being saddled will often hold its breath and tense its muscles while the girth is being tightened, thus making the girth appear tight, when, as a matter of fact, it is dangerously loose.

The principal object of this invention is to overcome the foregoing objections by providing a saddle with a girth which, when weight is applied to either or both stirrups, will be automatically tightened sufficiently to prevent turning although normally secured loosely enough to prevent discomfort.

30 A further object is to provide means for loosening the girth after the weight on the stirrups is removed or diminished.

Generally stated, the invention consists in connecting the ends of the girth to the stirrups through suitable straps and slidably supporting the straps so that when weight is applied to one stirrup, (or both), the corresponding strap will move in a direction such as to pull the girth more tightly about the horse.

40 The invention is illustrated in the accompanying drawing, wherein:

Figure 1 is a partly broken plan view of an English riding saddle to which the invention is applied;

45 Figure 2 is a section along line 2—2 of Figure 1;

Figure 3 is a perspective showing the relation and arrangement of the girth and stirrups; and

50 Figures 4 and 5 are fragmentary views of the different parts of the connection between the girth and stirrups.

The invention may be applied to various types of saddles, and is illustrated in the drawing as applied to the conventional English riding saddle having a pommel P, cantle C, jockey J, and skirt

5 S. In carrying out the invention, the stirrups 1 are connected to opposite ends of the girth 2 through stirrup supporting straps or end members 3, which are preferably slidably connected to and supported by the saddle. When applied to the saddle, each of the straps 3 may, if desired, extend from its corresponding stirrup to the adjacent end of the girth with its intervening portion slidably connected to the saddle. Preferably, however, each end member or strap is arranged to 10 extend from its corresponding stirrup slidably through the body of the saddle to the opposite end of the girth. In order to permit the straps to move relatively to the saddle, a back member 4 composed of a stiff material such as metal is 15 arranged within the body of the saddle, preferably between the conventional pad (not shown) and the seat proper. This back member is provided with grooves 5 through which the straps 3 pass. If desired, the grooves 5 may be made to 20 cross each other so as to bring the stirrups in the same relative position on opposite sides of the saddle instead of the off-set positions shown.

The outer ends of the straps 3 may be permanently or adjustably secured to the stirrup, but 25 their inner ends preferably are adjustably secured to the girth in any suitable manner as by the buckles 6. These straps are provided on the stirrup side of the grooved member 4 with stopping blocks 7 and on the girth side of said member 30 with similar blocks 8, these blocks being arranged to permit limited movement of the straps relatively to the saddle. The blocks 7 function as a means for holding the straps when the girth is being connected thereto, and thus permit the girth 35 to be snugly fitted or tightened manually as desired. Blocks 7 also limit the girth loosening movement after the girth has been automatically tightened. The blocks 8 function as a means for limiting the girth tightening movement of the 40 straps.

It will now be evident that the saddle may be secured to a horse simply by placing it upon the back thereof and connecting the inner ends of the straps or end members 3 to opposite ends 45 of the girth 2. In making these connections the straps 3 are manually pulled through the member 4 until the blocks 7 are brought into engagement therewith. The connections are then adjusted by means of the buckles 6 to the point 50 where the girth fits snugly against the belly of the horse without necessarily being tight enough to cause any substantial discomfort to the horse. As soon as the rider engages one foot in either of the stirrups and places his weight thereon, the en- 55

gaged stirrup will be forced downward, pulling the strap 3 through the saddle and thus tightening the girth sufficiently to prevent the saddle from turning. If the rider is heavy enough, this movement of the strap will bring the block 8 into engagement with the member 4 and thus prevent the girth from becoming any tighter. When the rider is seated on the saddle and the weight removed from the stirrups, the girth will again be brought to its original, relatively loose position by the breathing movement of the horse, such position being determined, of course, by the block 7. The return of the strap 3 to the loose position after it has been tightened may, if desired, be accomplished automatically. To this end a spring 9 is interposed between the member 4 and the block 8. The spring 9 is arranged to be compressed between the block 8 and the grooved member 4 when weight is applied to the corresponding stirrup so that it will return the strap 3 to its original loose position when the weight is removed from the stirrup.

It may be pointed out that a loose girth not only prevents discomfort but permits the muscles of the horse during its movement, to slide back and forth under the girth. This has the advantage of preventing the muscles from working against the edge of the girth and thus moving the saddle either forward or rearward, a result likely to occur unless the girth is made extremely tight.

Having described my invention, I claim:

1. A riding saddle having a stirrup supporting member which is adapted for connection to a girth and means for slidably connecting said member between the stirrup and the girth to the saddle.
2. A riding saddle having a stirrup supporting member slidably connected thereto and means for limiting the movement of said member relatively to said saddle.
3. A riding saddle having a stirrup supporting member slidably connected thereto to permit movement of the member in one direction relatively to the saddle when weight is applied to the stirrup, and means for moving said member toward its original position when weight is reduced.
4. A combination with a back member adapted to be fixedly secured upon a riding saddle, of means slidably secured to said member, said means being arranged on one side of said member

to support a stirrup and on the other side to engage a girth.

5. In combination with a riding saddle having a stirrup on each side thereof, of a girth, stirrup supporting means extending from a stirrup on one side of the saddle slidably through the saddle to the end of the girth on the opposite side of the saddle and stirrup supporting means extending from the other stirrup slidably through the saddle to the other end of said girth.

6. A riding saddle having an end member connected thereto, one end of which is adapted for connection to a girth, said member being arranged for movement in opposite directions relatively to the saddle respectively to tighten and loosen the girth, and a stirrup connected to said member so as to effect a girth tightening movement thereof when weight is applied to the stirrup.

7. A riding saddle having an end member connected thereto, one end of which is adapted for connection to a girth, said member being arranged for movement in opposite directions relatively to the saddle respectively to tighten and loosen the girth, a stirrup connected to said member so as to effect a girth tightening movement thereof when weight is applied to the stirrup, and means for limiting the movement of said member in one direction.

8. A riding saddle having an end member connected thereto, one end of which is adapted for connection to a girth, said member being arranged for movement in opposite directions relatively to the saddle respectively to tighten and loosen the girth, a stirrup connected to said member so as to effect a girth tightening movement thereof when weight is applied to the stirrup, and means for limiting the movement of said member in both directions.

9. A riding saddle having an end member connected thereto, one end of which is adapted for connection to a girth, said member being arranged for movement in opposite directions relatively to the saddle respectively to tighten and loosen the girth, a stirrup connected to said member so as to effect a girth tightening movement thereof when weight is applied to the stirrup, and means for resiliently opposing the girth tightening movement of said member.

JOSEPH A. GREENE.
